Julius C. Hochman, New York, N. Y.

Application July 7, 1949, Serial No. 103,405

39 Claims. (Cl. 139—11)

This invention relates to the art of weaving machinery and more particularly to high speed looms for weaving narrow strips of fabric.

As conducive to a clear understanding of the invention it is noted that heretofore where a loom utilizes reciprocating mechanism, the stress and strain incurred at the speeds used to give an economical output necessitates a machine having strong heavy parts which are relatively large and expensive and at best the speed of the machine is low as is the resultant output, and the wear of the parts due to the stress and strain may cause frequent breakdown and necessitate replacement of parts with the resultant stoppage of production.

With conventional heddle plates, the reciprocating stroke thereof is necessarily substantial and the machine must be run at relatively slow speed to avoid excessive shock and vibration with resultant low output. Even at such low speed, the shock and vibration, due to the movement of the heddle plates and the actuating mechanism therefor, is considerable and likely to cause frequent breakdowns with resultant stoppage for maintenance and repair.

Where the operating parts of the loom are exposed, the lint and dust generally prevalent in a mill tend to clog the loom, with the result that frequent stoppages are necessary for cleaning and replacement of parts with consequent reduction of output and enhanced cost of maintenance and furthermore the exposed parts are likely to cause injury to the operator.

If in order to change the pattern of the woven strip or to replace broken heddle wires or to change the number used or to tie broken threads, the loom must be partially disassembled, such adjustments result in loss in output during the relatively long time the machine remains idle.

It is accordingly among the objects of this invention to provide a weaving machine of the above type which is relatively compact and rugged in construction, and operates with a minimum of noise, in which the needle, the reed for beating the woven weft thread and the heddle plates are as close to the fell of the shed, and the heddle plates are as close to the fell of the woven strip as possible to minimize the stroke of the parts so as to get high speed with a minimum of shock and vibration, which utilizes uniform rotary motions wherever possible and has a minimum number of reciprocating elements, thereby minimizing the strain and wear inherent in high speed reciprocating machinery, which is capable of continuous operation for long periods without attention and at relatively high speeds, utilizing as it does moving parts that are light in weight, yet that are not delicate and hence not likely to become out of order, in which the working parts are readily accessible for maintenance and repair and the cost of upkeep of which is low, in which substantially all moving parts are fully enclosed running in oil to minimize clogging of the machine, to reduce wear thereof and to prevent injury to the operator, in which the pattern of the weave may quickly and readily be changed with but a few simple adjustments

2

and without disassembly of the machine, and in which broken heddle wires or heddle plates may readily be replaced and in which heddle wires may readily be rethreaded upon breaking of any of the warp threads.

According to the invention, vertically reciprocable narrow heddle plates of thin, preferably sheet metal stock, are mounted with a minimum of spacing therebetween and at such small distance from the fell of the shed, that the latter has substantially only the length required to accommodate the needle which is located to move through the shed in close contiguity to the fell and to accommodate the reed which practically fills, in its retracted position, the space between the path of the needle and the first heddle plate.

The shed is of small height conforming to its short length for which reason the stroke of the heddle plates as well as the stroke of the reed is correspondingly short. While separate mechanism could be used to reciprocate the heddle plates and the reed, it is preferred according to another feature of the invention to operate both the heddle plates and the reed from a rotary drive mechanism.

According to another feature, the rotary drive mechanism includes an endless chain having thereon rollers to operate the reed and removable cam keys to operate the heddle plates, whereby the device may be set to provide a selected pattern.

The needle is desirably triangular in cross section with an angle thereof adjacent the fell of the shed and preferably has a beveled nose portion to facilitate passage thereof through the warp threads.

The weft thread carried by the needle is desirably caught by a rotating hook and thereupon passed around a bobbin case which the rotating hook encompasses and around a border warp thread carried on a bobbin rotatably mounted in said bobbin case.

The reed is preferably in the form of a comb, the upstanding fingers of which straddle the warp threads in the shed, and the comb is desirably mounted on a pivoted member which may be oscillated through a short path between the first heddle plate and the fell.

According to another feature of the invention, substantially all of the cams, gears, driving rods and shafts are positioned in a central casing and preferably two weaving heads are provided, one at each end of the machine, both actuated by the same mechanism to provide enhanced output at a relatively low initial cost, the machine desirably being compact in size to enable one operator to watch several machines.

In the specific embodiment of the machine herein chosen to illustrate my invention, although many different arrangements could be used, a particularly desirable arrangement of the various cams, gears and sprocket wheels for operating the constituent elements of the machine is shown, arranged in timed relation to be driven by a common motor.

The general construction of the machine will first be described and then under appropriate titles will be described the component structural parts of the preferred specific embodiment shown herein.

GENERAL CONSTRUCTION

As shown in Fig. 3, the loom comprises a heavy, rigid, box-shaped, oil tight casing 35 open at the top thereof, and having an opening 42 at the bottom thereof closed by a plug 43 removable to facilitate draining of oil from casing 35. The casing 35 is desirably made from a unitary casting, with extensions 32 at each end thereof to each of which is desirably affixed, as by bolts 33, an upright or standard 34. The machine may be mounted on a table 36 and as best shown in Fig. 6, secured to such table by means of bolts 37 which pass through the bores 38 in bosses 38' positioned in extensions 39 and 41 on the front and rear respectively of the casing 35.

As the operating mechanism of the respective weaving heads at each end of the machine are substantially symmetrical and to all intents and purposes identical, it will

suffice to describe one of the weaving heads and the associated operating mechanism therefor. It will be understood, however, that while the duplex arrangement is preferred, an operative loom could, if desired, have only one weaving head.

As shown in Fig. 2, to afford convenient access to the interior of the casing 35, the open top thereof has a removable cover plate 44 affixed thereto by screws 45, cover plate 44 having an oval hand hole or opening 46 therethrough with an upstanding peripheral rim 47. The hand hole 46 is covered by means of an oval plate 53 which is secured to the face of rim 47 by screws 47' to prevent the entry of dirt or dust into the casing.

As shown diagrammatically in Fig. 1, a drive mechanism 15 is provided, comprising a main drive shaft 56 positioned transversely of the casing 35, and journaled in bearings 57 and 58 in front and rear walls 59 and 61 (see Fig. 4) respectively and protrudes beyond said walls. A drive pulley 55 is keyed on the drive shaft 56 near the rear end thereof and is connected desirably by a belt 54 to the drive motor (not shown) located beneath table 36. A hand wheel 62, which also acts as a flywheel, is affixed to drive shaft 56 at the end thereof adjacent pulley 55.

A sleeve 69 (see Figs. 1, 3 and 4) is affixed to the main drive shaft 56 by set screw 68 between bearings 57 and 58. Sleeve 69 which thus rotates with drive shaft 56, has spiral gears 73 and 74 at the front and rear end thereof, respectively. Gear 74 meshes with a spiral gear 75 keyed to a vertical transmission and crank shaft 76, the latter being journaled at its lower end in bearing socket 77 (see Figs. 1 and 3) on the floor of the casing and near its upper end in bearing block 78 rigid with and extending inwardly from the rear wall 61 of the casing 35. As gear 74 and gear 75 are of the same size, vertical shaft 76 will make one complete revolution for each revolution of the main drive shaft 56.

As seen in Figs. 1 and 3, affixed to the upper end of the vertical shaft 76 and protruding above bearing block 78 is a horizontal balanced crank member 81, which comprises a semi-circular counterweight 82 having an arm 83 extending radially therefrom. Pivotedly connected at one end as at 84 to the free end of arm 83 is a horizontal connecting rod 85, the free end of which has a hub 86 thereon with a vertical bore therethrough. Referring to Fig. 3, the reduced portion 87 of a vertical clamp member 88 is inserted through the vertical bore in hub 86, with shoulder 89 formed by reduced portion 87, resting on the top of hub 86. The clamp member 88 is pivotally retained in hub 86 as by a cotter pin 90 which extends through a transverse opening on the lower extremity of reduced portion 87, a washer 89 desirably being provided between the cotter pin and the bottom of the clamp member 88. Clamp member 88 has a hub 91 integral therewith at the upper end thereof having a transverse bore therethrough, through which a horizontal needle rod 51 extends, the latter being securely affixed in the bore of hub 91 by means of a set screw 92.

As shown in Fig. 3, rim 47 of hand hole 46 has opposed lateral bearing openings 48 therethrough each with an outwardly extending bearing 49 in which horizontal needle rod 51 is slidably mounted, the needle rod by reason of the gearing and linkage above described being moved back and forth at each complete revolution of the main drive shaft 56. Clamp member 88 is positioned directly beneath hand hole cover plate 53 to provide for convenient assembly of needle rod 51 through the transverse bore of clamp member 88, for properly adjusting the end to end position of needle bar 51 and for connecting it to the driving mechanism by means of set screw 92 and also to afford access to the hub 86 to permit ready insertion of cotter pin 90.

As shown in Figs. 1, 3 and 4, gear 73 on sleeve 69 meshes with a spiral gear 184 affixed near one end of a weft thread tension control sleeve 181 rotatably mounted 75 on horizontal transmission shaft 127 journaled in bear-

ings 128 and 129 (see Fig. 4) in the side walls 98 and 100 respectively of the casing 35, shaft 127 extending beyond bearing 129. As gears 73 and 184 are of the same size, sleeve 181 will make one complete revolution for each revolution of the main drive shaft and hence tension control cams 182 and 183 which are also rigidly affixed to sleeve 181 and offset 180 degrees with respect to each other will operate the weft thread tension control devices 231 and 232, respectively, as shown in Fig. 4.

Affixed on the end of sleeve 181 opposed to gear 184 is a spur gear 185 which drives a hook shaft spur gear 186 fixed on a horizontal hook shaft 187. As the ratio of gear 185 to 186 is illustratively two to one, hook shaft 187 will make two revolutions for every revolution of the main drive shaft 56 and each reciprocation of the needle rod 51.

Hook shaft 187 is journaled in bearing 188 (Fig. 4) in side wall 98 of the casing and in an elongated bearing bore 189 extending through a horizontal boss 191 unitary with and extending longitudinally along the inner face of the casing and which boss provides for an intermediate bearing support as at 192 and for an end support 193 for the rapidly rotating hook shaft 187.

Affixed to vertical shaft 76 near the lower end thereof above bearing 77 is a worm 93 which meshes with a worm gear 94 keyed on a horizontal pattern and reed control shaft 95. The latter, as best seen in Fig. 3, is journaled in bearings 96 and 97 on the inner faces of the left side wall 98 and right side wall 99 of the casing 35 and extends beyond said side walls, the shaft 95 being restrained from lateral movement, as shown in Fig. 3, by collars 95' affixed to shaft 95 by set screws 96'. The ratio of worm 93 to worm gear 94 is illustratively 4 to 1. Thus shaft 95 will rotate 90 degrees for each complete revolution of vertical shaft 76 and each reciprocation of the needle rod 51. Affixed on shaft 95 within casing 35, as shown in Figs. 1, 3 and 4, is a worm 119 which meshes with a worm gear 121, affixed on the lower end of a vertical counter shaft 122, the latter being journaled in a long vertical bushing 123' affixed by set screw 124' in a bearing block 123 extending laterally inwardly from and desirably integral with the inner face of front wall 59 of the casing.

In the embodiment shown herein the ratio of worm 119 to worm gear 121 is illustratively 15 to 1. Thus it will require 15 revolutions of worm 119 to turn worm gear 121 one revolution. As shaft 95 turns one quarter of a revolution for each revolution of the main drive shaft 56 and each reciprocation of needle rod 51, it will take 60 revolutions of the main drive shaft 56 to turn counter-shaft 122 one revolution.

Affixed on countershaft 122 near its upper end which extends beyond bearing block 123 is a worm 124, the lower end of which is seated on bushing 123' as shown in Fig. 3. The upper extremity of shaft 122 is threaded to receive a nut 125 which securely holds worm 124 on shaft 122. Worm 124 meshes with a worm gear 126 which is affixed on horizontal take-up tension shaft 127. The ratio of worm 124 to worm gear 126 is illustratively 1 to 4. It will therefore require four revolutions of the countershaft 122 to turn horizontal shaft 127 one revolution. As it requires 60 revolutions of the main drive shaft 56 to turn countershaft 122 one revolution, it will require 240 revolutions of the main drive shaft 56 to turn worm gear 126 and take-up shaft 127 one revolution.

A horizontal fabric take-up shaft 138 is positioned near the top of the casing 35 adjacent to and in front of the front wall 59 and journaled near its mid-point in a bearing block 142 (see Fig. 2) affixed to front wall 59 of the casing and near its ends in bearings 144 and 144' formed in the upper portions of standards 34 respectively and extends beyond said bearings 144 and 144'. Shaft 138 is driven through a transmission from a changeable take-up gear 132 which is desirably keyed on the end of shaft 127 protruding beyond bearing 129 in side wall 100 and

removably affixed on said shaft 127 by a nut 131 (see Figs. 4 and 7). Take-up gear 132 meshes with an idler gear 133 rotatably mounted on an adjustment plate 134 and secured thereto by a nut and bolt 135. The adjustment plate 134 has an arcuate slot 136 at its lower end through which a stud 137 secured to side wall 100 extends, thus permitting the plate 134, which is pivoted on take-up shaft 138, to be moved. A nut 139 threaded on the free end of stud 137 enables the plate to be retained in adjusted position. Idler gear 133 meshes with a spur gear 141 (see Figs. 1 and 7) keyed on horizontal take-up shaft 138 to rotate the latter.

With the adjustable drive mechanism thus described for the take-up shaft 138, it is thus convenient to change the speed of rotation of shaft 138 in accordance with the number of picks per inch, it is desired to weave in the finished product. The details of this operation will be further described hereinafter.

Having thus described the general construction of the driving mechanism of the loom, the component parts of the weaving heads will now be described in detail.

I. Shed forming

(a) NEEDLE STRUCTURE (Figs. 14, 14^a)

Each of the weaving heads has a weft thread carrying needle associated therewith respectively designated by the numerals 52 and 52'. As the needles are identical, only the former, i. e., needle 52 is shown in Figs. 14 and 14^a. The needle which is relatively narrow in width, desirably has a right angled extension 25 at the rear end thereof by means of which it is affixed, as shown in Fig. 19, as by a screw 27, to the flattened end 26 of the needle rod 51, the rear end of extension 25 abutting against shoulder 26' formed at flattened end 26. The nose 29 and the rear end of each of the needles are provided with openings or eyes 30 and 30', respectively, through which the weft thread W may be threaded as shown in Fig. 14^a and a broad notch 28 is provided in the underface of the needle at the nose thereof.

The needle shank desirably has a flat top to provide strength and substantially the entire length thereof is triangular in cross section as shown in Fig. 11 so that it may fit into the vortex of the substantially triangular shaped shed formed in the warp threads as hereinafter described. The nose 29 of the needle is beveled at 29' so that as the needle is moved through the shed it may push away loose filaments of the warp thread which tend to cling together in the shed and block the needle path and also deflect any sagging warp threads.

The triangular shape and narrow width of the needle thus permit it to be located close to the feel of the shed thereby minimizing the space required therefor.

(b) HEDDLE PLATE ASSEMBLY (Figs. 2, 3, 5, 8 and 13)

In order to provide the shed through which the needle may pass to weave the strip which will illustratively be shown and described as an elastic strip, having border threads of rubber with five intervening rubber threads 60 and with the remaining eighteen threads being of cotton, a heddle plate assembly is provided. It is of course to be understood that the entire strip could have only cotton threads or more or less rubber threads could be used.

As shown in Figs. 2, 3, 8 and 13 this assembly desirably 65 comprises a pair of spaced, parallel upstanding heddle plate guides 291 and 292 positioned between standard 34 and the side wall 98 of the casing. As shown in Fig. 5, a guide plate 291 is affixed by screws 294 to the inner face of standard 34 with the rectangular portion 293 thereof protruding above the standard, and a guide plate 292 (Fig. 8) is affixed by four screws (not shown) threaded into the upper holes 295 (Fig. 6) in a pad 296 integral with the outer face of side wall 98 of the casing. In order properly to position the guide plates when affixed to their respective supports so that the vertical nar-

row guide slots 297 (Figs. 13 and 23) on the opposed faces thereof will be transversely aligned, a pair of dowels 298 (Fig. 6) is provided in pad 296 and a corresponding pair 299 (Fig. 5) in standard 34 which fit into corresponding openings in the guide plates 291 and 292 respectively. The four lower screw holes 295' in the pad 296 are used to secure the warp thread guide bars (not shown) to the casing 35.

After the guide plates have been affixed as above set forth, a long bolt 303, as shown in Fig. 2, is inserted through standard 34, guide plates 291 and 292 into a threaded opening 296' in pad 296 with a sleeve 304 (Fig. 2) encompassing the bolt to act as a tie rod for standard 34 and as a spacer between the guide plates 291 and 292.

Slidably mounted in each pair of aligned slots 297, of which twelve pairs are illustratively shown in Fig. 13, is a heddle plate generally designated by the numeral 305 and specifically referred to by the numerals 305¹ to 305¹². The guide slots 297 are desirably spaced only 0.1 inch apart with the slots 297 carrying heddle plate 305¹² being spaced .125 inch from the slots carrying heddle plate 305¹¹ to provide for heavier heddle wires in plate 305¹² to accommodate the highly tensed and relatively thicker rubber warp threads which heddle plate 305¹² illustratively controls in the embodiment herein described. As shown in Figs. 21 and 22, each heddle plate may preferably be formed from a blank desirably of thin light weight metal which comprises a short leg 308 rising from one end of a base 307 and having laterally inward projecting tongues 309 integral therewith near its root end and near its upper end, each tongue having ears 311 at the upper and lower edges thereof bent at right angles to the tongue. Upstanding from the other end of base 307 is a short leg 312 which when initially formed is tilted from the vertical, as shown in Fig. 22. Desirably integral with the leg 312 near the base 307 and at the top thereof are laterally extending short arms or rails 313 and 314 at right angles to leg 312 and lying in the same plane therewith. Thus it can be seen that arm 313 is spaced from leg 308 as at 315 and arm 314 is spaced from the upper end of leg 308 as at 316. The heddle plate also has a flexible finger 317, extending downwardly from base 307 in the same plane and integral therewith. Leg 312 may be bent until it is parallel to leg 308, in which position the ends of arms or rails 313 and 314 will be aligned with the respective tongues 309 on leg 308 and positioned behind such leg.

As seen, the heddle plate is of order of thickness no greater than the heddle rails 313 and 314 and is preferably as described an integral stamping with said rails. The thickness of the heddle rails is of the order of the width of a slot which can be made in a standard narrow heddle wire, all as shown in Fig. 21. The term "thin" as applied to the heddle plates in certain of the claims is a thickness such as defined in this paragraph.

To complete the assembly of the heddle plate, a plurality of very short heddle wires 319, only one of which is shown, are mounted on each of the heddle plates. To this end each heddle wire 319 desirably comprises a flat wire, as shown in Fig. 21, and having an eye 327 through its midpoint 326 into which a warp thread may be inserted and also desirably having a slot 321 at each end thereof through which may be passed arms 313 and 314, when the ends of the latter are moved slightly away from leg 308. With ears 311 straddling the ends of arms 313 and 314, an eyelet, split rivet or other readily detachable connecting elements 322 is thereupon passed through openings 323 and 324 in the tongues 309 and arms or rails 313 and 314 and headed to complete the assembly, the removable character of connecting element 322 facilitating speedy replacement of broken heddle wires or removal or addition of heddle wires as required.

With the heddle plate 305 assembled as shown in Fig. 21, a slot 320 is thereby provided between arm 313 and

base 307. Thus the heddle wires may readily be moved laterally along the lengths of arms 313 and 314.

The short legs 308, 312 provided for the use of extremely short and therefore stiff heddle wires, while the short arms 313, 314 form extremely stiff rails on which the heddle wires are mounted. This special construction provides simple, light weight heddle units, which are even stronger than the large, heavy construction of conventional looms, and yet so light in weight as to permit very high speed operation.

In order that the relatively small space between the parallel adjacent heddle plates be sufficient to accommodate the latter without contact when they are mounted between the guide plates, as shown in Fig. 13, the legs 308 thereof are alternately positioned so that no two riveted portions of successive heddle plates will be aligned.

With the construction and arrangement of the heddle plates herein described, it is apparent that the distance between heddle plates 305¹ to 305¹² will be only slightly greater than one inch, thus providing an extremely compact arrangement and a very short vertical movement of even the most distant heddle plate 305¹, yet as the heddle plates and short heddle wires are stiff and strong by reason of their special construction above set forth, such compactness is without loss of strength or durability.

(e) HEDDLE PLATE ACTUATING MECHANISM
(Figs. 5, 8 to 11 and 13)

Associated with the heddle plates 305¹ to 305¹² is the operating mechanism therefor comprising a plurality of levers 328, illustratively thirteen in number, twelve of which correspond to the number of heddle plates 305 plus an additional lever for heddle plate 305¹² which, as shown in Fig. 9, preferably is operated by two levers for the reason hereinafter set forth. Each of the levers 328 (specifically numbered 328^{12a} and 328¹ to 328¹² inclusive, as shown in Fig. 8, with levers 328^{12a} and 328¹² operating plate 305¹) is pivotally mounted near its mid point on a transverse rod 329 positioned at one end in a socket 331 on side wall 98 of the casing and extends through a threaded opening 332 in standard 34, the entire set of levers being positioned between collars 333. In order properly to space the levers 328 on rod 329, washers 337 encompassing the rod are interposed between consecutive levers. The outer end of rod 329 is threaded as at 335 and has a nut 336 thereon securely to lock the rod in position.

Each of the levers 328 has a roller 338 (Fig. 11) rotatable in a slot 334 formed therein. A coil spring 339 is affixed at its lower end to an opening 341 in the rear end of the lever. The upper end of the coil spring is connected to the end of an adjusting screw 342 (Fig. 8) extending upwardly through a horizontal support bar 343 affixed between standard 34 and side wall 98 of the casing. The protruding ends 344 of the screws each has a nut 340 threaded thereon and by means of which the tension on the spring 339 may be adjusted, thereby varying the tension on lever 328, the nuts 340 being locked against accidental rotation by a central upstanding ridge 343' on the upper face of support bar 343.

To provide room for springs of large size and long life, the rear ends 350 of adjacent levers, as shown in Fig. 11, alternately vary in their distance from pivot rod 329, thus arranging the springs in two parallel rows and the associated adjustment screws 344 are correspondingly spaced on support bar 343, as shown in Fig. 2.

In order to limit the pivotal movement of the levers 328 under the pull of springs 339, a stop bar 329' desirably of fibre, is provided affixed between wall 98 and standard 34 by screws 330' (Figs. 5 and 11). The lower end of the stop bar 329' is desirably beveled as at 331' so that the levers 328 will engage with the width of the stop bar.

As the distance of heddle plate 305¹ from pivot rod 329 is greater than that of heddle plate 305¹², it is apparent that the length of the portion of the levers from

the rod 329 to the front end thereof will vary respectively, depending upon which of the heddle plates the associated lever actuates. However, as one of the heddle plates, i. e., heddle plate 305¹², which in the embodiment herein carries all but one (i. e. the bobbin warp thread) of the normally highly tensioned rubber warp threads utilized in the woven strip of fabric, a finger 317 is desirably provided on each side of heddle plate 305¹². Consequently the levers 328¹² and 328^{12a} near each end of rod 329 which both desirably actuate heddle plate 305¹² are both of the same length and ensure that the tension of the rubber threads will not cause heddle plate 305¹² to tilt when moved up and down and bind in its guideways or grooves 297.

In addition to heddle plate 305¹² being spaced from plate 305¹¹ by a greater distance than the spacing of the others and desirably differing from the other heddle plates in that it has two fingers 317, it also differs therefrom in that the distance between transverse arms 313 and 314 is less. Thus heddle wires 319 thereof are shorter, with a corresponding increase in strength to enable such wires to withstand the strain of the plurality of tensed rubber warp threads.

As shown in Fig. 9 lever 328¹¹ is connected to finger 317 of heddle plate 305¹¹ which is to the rear of the rubber heddle plate 305¹². Consequently lever 328¹¹ is slightly longer than levers 328¹² and 328^{12a} with finger 317 of heddle plate 305¹¹ being slightly to the right of finger 317 of heddle plate 305¹². This arrangement continues progressively until the twelfth or last heddle plate 305¹ which is farthest from rubber heddle plate 305¹² and consequently will have the longest lever arm 328¹ and the finger 317 thereof will be slightly to the left of finger 317 of rubber heddle plate 305¹² which coacts with lever 328^{12a}.

It is to be noted that as lever 328¹ is the longest, its throw will be greater than that of levers 328¹² and 328^{12a} and consequently heddle plate 305¹ will move up and down a greater distance than rubber heddle plate 305¹². In order that the heddle plates and the heddle wires substantially conform in size to facilitate mass production thereof, all the heddle plates, except the rubber heddle plate 305¹², are made the same size between the arms 313 and 314 thereof as the heddle plate 305¹, which latter requires the maximum distance between arms 313 and 314 thereof in order to provide clearance for the warp threads passing therebetween. For the same reason heddle plate 328¹ is identical with heddle plate 328¹¹, heddle plate 328² is identical with heddle plate 328¹⁰ etc., merely turning the heddle plate over resulting in positioning flexible finger 317 symmetrically on opposite side of the center line. Thus only seven different kinds of heddle plates are needed for the twelve heddle plates shown.

To provide a long wear life of the small machine elements involved as well as to provide a free pivotal action between the ends of the levers and the ends of flexible fingers 317 of the heddle plates to which they are connected, a rocker type joint is desirably provided with the parts thereof adapted for ready manufacture of the hardest metallic substance. To this end as shown in Fig. 11 each of the levers has an arcuate cavity 351 therein in which the transverse tip 318 at the end of each of the corresponding fingers may be positioned, which tip preferably is made separate from the finger and welded thereto. Tip 318 is retained in its seat by a cap member 352 affixed to the lever by screw 354 and having a corresponding arcuate cavity 353 therein. As tip 318 and cap 352 are desirably made of tungsten carbide or other wear resistant material, they will have a long life.

(d) PATTERN CHAIN ASSEMBLY
(Figs. 8, 9 and 11)

To reciprocate the heddle plates 305 in predetermined cyclic sequence to form the shed required for the weaving operation, a pattern chain assembly is provided which is constructed and arranged to permit setting up of even

complicated patterns with ease and rapidity and also to permit ready and convenient changes in the pattern without disassembling the machine and with the resultant enhanced production and reduced cost of operation. To this end the pattern chain assembly includes a wide sprocket wheel 101 having a plurality of circumferential grooves therein illustratively thirteen in number as shown and designated by the numerals 112¹² and 112¹ to 112¹² inclusive as shown in Figs. 8 and 9. Sprocket wheel 101 is affixed to the end of shaft 95 between side wall 98 of the casing and standard 34 and has riding thereon a continuous pattern chain 102. The latter as shown in Figs. 1 and 5, extends through openings 203 and 104 in extension 32 and table 36 respectively and is stretched between sprocket wheel 101 and an idler sprocket wheel 105 mounted on a shaft 106 supported by and vertically adjustable in brackets 107 affixed to the undersurface of table 36. Thus the position of idler sprocket wheel 105 with respect to sprocket wheel 101 can be adjusted vertically in accordance with the length of the pattern chain being used. As shown in Fig. 1 the idler sprocket wheel and a portion of the pattern chain are enclosed in an oil case 108 affixed beneath table 36 to lubricate the chain and to prevent dust and dirt accumulating thereon and also to avoid accidental soiling of the woven material or injury to the operator.

Pattern chain 102 preferably comprises side links 109 which are joined by elongated transverse cross pins 111 each of which has a plurality of parallel annular grooves 110 therein, illustratively thirteen in number corresponding to the number of levers 328 and the number of grooves in sprocket wheel 101.

Pattern chain 102 has a roller 113 rotatably mounted thereon at each end of every fourth cross pin. Thus at every revolution of the main drive shaft 56 and every reciprocation of needle rod 51, sprocket wheel 101 will rotate 90 degrees thereby moving each roller thereon through an angle of 90 degrees around sprocket wheel 101.

In order to provide for greatest ease and speed of pattern change, pattern cam keys 114 are provided, shown in Fig. 11, and adapted to fit into the aligned groove 110 of two successive cross pins. Each key desirably comprises a yoke-shaped cam member of resilient material having an arcuate groove 115 in opposed edges of each of the legs 116 thereof. The pattern key is fitted into two aligned grooves 110 with the legs 116 thereof straddling the successive cross pins 111 and extending therebelow into groove 112 in sprocket wheel 101. The resilient legs 116 thus grasp the cross pins 111 securely to hold the pattern key in position. The lower inner extremities of each of the legs 116 are beveled as at 155 to facilitate insertion of such legs over the cross pins 111 and the lower outer extremities of each of the legs 116 are beveled as at 156 so that the legs of adjacent keys may clear each other as the chain curves and passes around the sprocket wheel. The upper portion or cam edge of the pattern key which extends upwardly above the level of the teeth of the sprocket wheel 101 may have a gradually inclined surface 117 or 117', or an arcuate surface 118, which cooperate with the associated roller 338 on a lever 328 to raise, lower or hold the latter and reciprocate the heddle plates in accordance with the requirements of the pattern to be woven. Each of the grooves 110 and 112 is of sufficient width to permit the legs of two pattern keys to be inserted therein in side by side relation, and as the extending legs of the keys fit into the grooves 110 in cross piece 111 and grooves 112 in sprocket wheel 101, the keys will not vibrate or tilt when they abut against the roller 338.

In order to prevent accidental soiling of the woven material or injury to the operator, a protective plate 252 is provided, mounted between standards 34 and side walls 98 so as to cover the pattern chain and is secured by screws 253 to the extension 39 in the front of the loom.

II. Weft thread controls

(a) TENSION CONTROLS
(Figs. 2, 4, 4a, 4b and 19)

In order to control the tension on the weft threads W and W' which illustratively extend from spools S and S' respectively through eyes 30' and 30 at the rear and nose of each of the needles, the tension devices 231 and 232 heretofore mentioned and tension arms 255 and 255' are desirably provided.

Tension devices 231 and 232 which are identical, are shown in Figs. 4, 4a, 4b and Fig. 19 and are mounted on the front wall 59 of the casing. As shown in Figs. 4a each tension device preferably comprises a bushing 233 which extends through front wall 59 and protrudes therefrom on both sides thereof. Bushing 233 has a rod 234 therein, slit or bifurcated as at 234'. Bushing 233 is reduced as at 237 near the inner end thereof to form a bearing 237' and enlarged as at 238 to retain cam follower ball 239. Encompassing rod 234 and seated against shoulder 235 formed by the end of bushing 233 are a pair of tension discs 241, the rims 242 of which form a groove 243 therebetween when the discs are in juxtaposition, in which a thread may be inserted to slide between said discs 241. A clamp disc 244 having a cross bar 245 across the opening 246 therein also encompasses rod 234 with the cross bar extending through slit 234' and the rim 247 of the clamp disc is urged against tension discs 241 by a coil spring 248 encompassing said rod 234 and retained theron by tension adjusting nut 249 screwed on the threaded outer end of rod 234. A slidably mounted releasing rod 251 extends through axial bore 236 of rod 234 and bearing 237' of bushing 233 and is confined between cross bar 246 at one end and ball 239 at the other.

Associated with said tension devices 231 and 232 are the identical tension control cams 182 and 183 respectively. Thus, as follower ball 239 of each of the tension devices is retained against the rim of its associated cam 182 or 183 and forced outward by such rims the rods 251 will alternately reciprocate as the cams rotate, thereby to relieve the pressure of clamp disc 247 against tension discs 241 to relieve the pressure on the thread therebetween.

Tension compensation arms 255 and 255' which are identical as shown in Fig. 2 are mounted respectively near each end of the cover plate 44 at the front of the machine. As shown in Figs. 2a and 19, each tension compensation arm is desirably mounted on a base 256 slidably affixed to the cover plate in slots 257' by bolts 256' and has an upstanding ear 257 at right angles thereto extending past the front edge of the cover plate 44.

A tension adjusting screw 258 machined so as to be substantially square in cross section as shown in Fig. 2b is inserted through a correspondingly square opening 261 in ear 257. A knurled tension adjusting knob 262 which is threaded on the end of the screw 258 has a slot 263 in its shank 264 transversely thereacross. A substantially U-shaped spring clamp 265 is provided having an arcuate bend 266 in one leg thereof which, when the clamp is placed over the shank 264, will encompass the periphery of the latter with leg 267 of the clamp lying in slot 263 against a flat surface 268 of the adjusting screw.

The free end of adjusting screw 258 has an eye 271 therein to which one end of a coil spring 272 is connected. The other end of the coil spring is connected to an eye 273 at the end of an arm 274 pivoted at its mid point by a screw 275 to base 256. The free end of arm 274 has an upstanding portion 276 integral therewith with an opening 277 therein through which a weft thread may pass.

By the arrangement herein described, the position of the tension compensation devices may be shifted along

cover plate 44 to vary the position of such devices with reference to the needle positions at the inner and outer extremities of the needle bar stroke, according to the width of the fabric being woven, and the weft thread tension may be adjusted even when the machine is operating, by merely rotating adjusting knob 262.

Positioned adjacent the tension compensation device 255 and rigid with the cover plate is a guide bracket 278 (Fig. 19) the laterally extending leg 279 of which has a pair of openings 281, 281' therein through which the weft threads W and W' may be inserted. A guide bracket 282 shown in Figs. 2 and 3, is also provided adjacent tension device 255', which has an upstanding arm 283 through which weft thread W' may pass, the latter being threaded through an upstanding guide 290 affixed to the front wall of the casing.

(b) WEFT THREAD SLACK TAKE-UP DISCS
(Figs. 4, 6, 19, 20)

Associated with the weft threads W and W' from spools S and S' are a plurality of slack take-up discs 63, 64 and 65 affixed in coaxial relation on the end of shaft 56 which extends through bearing 57 on the front wall 59 of the casing.

As can be seen from Fig. 20, disc 63 has a mounting hub 60 at its axis affixed to shaft 56. Discs 64 and 65 are not directly affixed to shaft 56 but disc 64 is coaxial with disc 63 and affixed thereto by an arcuate connecting web 66 which joins the discs 63, 64 near the periphery thereof with a slight space therebetween. The third disc 65 is coaxial with disc 64 and affixed thereto by an arcuate connecting web 67, 180 degrees removed from web 66 and which joins the discs 64 and 65 near the periphery thereof also with a slight space therebetween.

35 (c) WEFT THREAD LOOPING CONTROL.—(1) HOOK
AND BOBBIN ASSEMBLY
(Figs. 13a, 15, 16, 17, 18, 23, 24)

Each end of hook shaft 187 which protrudes well beyond bearings 188 and 193 has a rotary hook member 195 thereon with a hub 197 affixed to the hook shaft by means of set screws 196 (Figs. 15 and 17).

The hook member 195 is substantially cup-shaped in configuration and has an outwardly diverging recess 401 extending the height of its side wall 400 so that each end 402, 403 of the side wall forms an obtuse angle with the edge of the rear wall 202 of the hook member. The edge of the forward end 402 of the side wall 400 is beveled as at 404 and a metal strip 405 is welded along said edge so as to form a weft thread engaging hook having a notch 406.

As clearly shown in Fig. 24, an arcuate slot 407 is provided in the periphery of the hook member in the rear wall 202 thereof, from the leading edge of notch 406 to nearly the edge 403. The open mouth 198 of hook member 195 facing toward standard 34 has nested therein a substantially cup-shaped bobbin case 199 with the rear wall 300 of the case slightly spaced from the rear wall 202 of the hook member. Integral with the bobbin case 199 at the top thereof and extending upwardly from the outer edge 407' thereof which extends outwardly as at 408' is a support plate 408 having an inclined slot 409 therethrough which extends into the bobbin case. The support plate 408 has a tooth 202' extending laterally outward and upward therefrom which, as shown in Fig. 13a, passes through an opening 209 in an arm 204 affixed by screws 205 to the upper end of standard 34 on the outer side thereof. Thus as hook member 195 is rotated by hook shaft 187, bobbin case 199 will be loosely supported and restrained from rotation.

The end wall 300 of the bobbin case 199 has an axial resilient split collet 206 rigid therewith and extending axially forward therefrom on which a bobbin 207 of large diameter and capacity may be rotatably mounted, the resilient forward end of collet 206 being preferably formed with outwardly extending ears 206' which normally maintain the bobbin in position on the collet. The

bobbin has openings 207' therein in which a hook may be inserted to facilitate its removal from the collet 206. The hook member 195, bobbin case 199 and bobbin 207 are positioned in a substantially arcuate recess 208 (Fig. 13a) in the upper end of standard 34.

A support horn 211 is provided rigid with support plate 408 and extending laterally inward therefrom over the hook member 195. Support horn 211, which tapers downwardly toward its free end as shown in Figs. 15 and 17, has a groove 212 along the top edge thereof and a notch 213 near the affixed end thereof leading into said groove 212. The free end of the support horn has a temple or edge wire 214 affixed thereon at right angles thereto extending toward the front of the loom which acts to maintain the width of the woven strip in the manner hereinafter described.

The thread from the bobbin designated by the letter R, which in the embodiment shown, illustratively is of rubber, passes through slot 409 in support plate 408, through slot 215 in the bobbin case 199 and behind a resilient tension arm 216 adjustably secured to support plate 408 by screws 217. The arm 216 has a curved end portion 218 which acts as a guide to direct the thread which will pass behind the arm and be frictionally tensed between such arm and the rear face of support plate 408 and also retains the thread in the groove 212 in top of support horn 211.

Referring to Fig. 13a, the loom operator is protected by a cover 221 hinged to the top of the standard 34 as at 222 and curved over the top of support horn 211 and the hook member 195, the free end 223 of the cover being releasably retained closed against the top of the standard by spring latch 224.

To cover the side of the bobbin case as shown in Fig. 8 a cover plate 225 is also provided and is affixed by screws 226 to the side edge 227 of the cover 221. Thus when the cover is pivoted upwardly about its hinge 222, the bobbin will be readily accessible.

III. Reed (Figs. 8, 9, 10, 11 and 12)

In order to beat the weft thread as it is woven, a light weight and short stroke reed 361 is provided which desirably comprises a thin sheet metal plate 362 curved near the upper end thereof as at 363 and having a laterally extending stiffening wall 364 on each side edge thereof at right angles to the convex face of the plate. The side walls 364 extend beyond the lower edge 365 of the plate to form a yoke, the arms 366 and 367 of which are pivotally mounted on the outer face of the end wall 98 of the casing by a screw 368 and on the inner face of the standard 34 by screw 369. The arms each have a curved notch 371 therein (Fig. 10) which provides clearance for rod 329 on which the levers 328 are mounted.

Extending from each of the walls 364 in the same plane thereof are fingers 372, each having a coil spring 373 affixed at the end thereof as at 374. As shown in Fig. 8 the upper end of the coil spring is connected to the eye end 375 of a screw 376 extending through mounting block 343 and held therein by a nut 377 by means of which the tension on spring 373 and hence on reed 361 can be adjusted, nut 377 being locked against undesired rotation by central ridge 343' formed on block 343.

Arms 366 and 367 respectively at the lower extremity of the reed each has a roller 378 (Fig. 10) mounted on the inner face thereof each affixed thereto by a shouldered screw 379. The rollers are aligned with the rollers 113 on the pattern chain 102 to be periodically engaged thereby as the pattern chain rotates in the manner hereinafter set forth.

As shown in Figs. 9 and 19, the plate 362 at its upper end carries a readily detachable comb-type reed unit having a plurality of upright fingers 381 so that each finger may be straddled by a number of warp threads as desired.

The comb unit as shown in Figs. 9 and 12 comprises

a rod 383 desirably threaded at each end thereof and preferably formed with an integral shoulder 394 at one end having an integral key 395. The fingers 381, each of which has an integral hub portion 382, are assembled on rod 383 with intervening spacing washers 384 as may be required by the fabric to be woven. The fingers and washers are thereupon securely clamped together against shoulder 394 by a nut 396 (Fig. 9) threaded on the end of rod 383.

To mount the reed unit on plate 362, the right hand end of rod 383 is slipped into a hole in the corresponding side wall 364 of the plate 362 and the key 395 at the left hand end of rod 363 is positioned in the U-shaped notch 385 in the corresponding side wall 364. The reed unit is thereupon securely affixed to plate 362 by means of lock washers 386 and nuts 387 threaded on the ends of rod 383.

By reason of key 395 in notch 385 and as the fingers 381 extend upward from the hub portion 382 at an angle thereto, with the base 388 thereof seated against the face of plate 362, the fingers will not rotate on rod 383 and in back position as best shown in dot and dash lines in Fig. 10 the fingers will be parallel to the heddle plates between the rubber heddle and the fell B of the woven article. In order accurately to locate the comb or reed in its outermost position to prevent the fingers of the reed from striking the heddle plates, and to provide a clear passage for the movement of the needle, a stop 389 is provided therefor close to its top or operating end against which plate 362 may abut.

As shown in Fig. 23 the stop 389 comprises a substantially U-shaped member having a beveled cross piece 422. The arms 423 of the stop are affixed to the front edges of the heddle guides 291, 292 by screws 424 and notches 425 are provided in such arms 423 which act as bearings or guides for the needle as it reciprocates.

As can be seen by particular reference to Fig. 9, the back and forth movement of the reed is extremely short and entails a vibratory movement of only a few degrees, this slight movement together with the light weight of the comb permitting substantially shockless operation at high speed.

IV. Table plate (Figs. 13, 15, 15a and 23)

Affixed at each end of the machine to standard 34 and to cover plate 44 which it overlaps, is a table plate 391 over which the woven strip passes. Affixed to the table plate by screws 392 is a U-shaped hinge member 411 the arms 412 of which loosely straddle the end of a bridge 413 preferably of resilient metal, extending transversely across the woven strip which passes therebeneath and which is pivotally and loosely connected to said arms by a pintle 414. The free end of the bridge has a downwardly and outwardly directed lip 415 integral therewith, which lip 415 is slid under the table plate 391 beyond a notch 417 in the latter as shown in Figs. 13 and 23. As the free end of the resilient bridge will normally be urged upward from the table plate by reason of abutting portion 418 on the bottom face thereof adjacent hinge 411 when lip 415 is positioned beneath the table plate, the lip will be retained securely in position by the frictional drag of the moving fabric, but the bridge is capable of being freely lifted without the use of tools when required, as in tying in a broken warp thread in the operation of the loom.

Affixed on the table plate 391 as shown in Figs. 15, 15a and 23 in juxtaposition to the end of support horn 211, spaced from bridge 413 so as to permit pivotal opening of the latter, and mounted on a pin 395, is an upstanding roller 420 against which support horn 211 bears and between which the weft thread slides in the manner hereinafter described.

The position of the roller 420 closely adjacent the edge wire 214 prevents frictional drag of the weft threads sliding along the temple or edge wire and the tensed bobbin thread R from pulling the horn out of position which

would cause it to shift and pivot the bobbin case so that tooth 202' would press tightly against the sides of opening 200 and thus prevent free escape of the weft thread loop.

An upstanding guide piece 421 preferably integral with and rising from the table plate 391, is aligned with the slot 407 in the periphery of the hook member to guide the weft thread W therein as the hook pulls the weft thread loop around the bobbin case.

V. Fabric tension take-up mechanism (Figs. 2, 3, 3a, 5a, 8)

A fabric take-up mechanism is provided to supply constant tension on the warp threads as the fabric is woven and to take up the woven strip at a predetermined rate.

This mechanism as shown in Fig. 2 includes a driven sleeve 145 encompassing the respective ends of take-up shaft 138 and rotatably mounted thereon. The sleeve is journalled in bearings 144 and 144' in standards 34 and extends therefrom, said sleeve having an annular take-up drum 146 integral therewith.

The inner end of each drum 146 has a toothed face 147 which may mesh with the correspondingly toothed face 148 of a driving member 149 which is slidably keyed on shaft 138, and encompasses the latter to form a clutch.

As shown in Fig. 3a, driving member 149 has a radial hole through one side thereof in which is lodged a steel ball 151 which is urged into a depression 154 in shaft 138 by a coil spring 152 retained in said hole by a screw plug 153. When teeth 147 and 148 are engaged, the ball 151 retains the driving member 149 in driving position and when said teeth are disengaged, take-up drum 146 may be rotated by rotating hand wheel 155 affixed as by key 150 to the outer ends of each of the sleeves 145. A second depression 154' is provided in shaft 138 to retain the clutch in open position.

As shown in Fig. 3, drum 146 preferably has a fine knurled periphery which coacts with a horizontal tension roller 158 to provide tension on the fabric as it is being woven, in the manner hereinafter described. As shown in Fig. 5a, roller 158 which preferably has a rubber surface, is idly mounted on a horizontal rod 159 affixed between the legs 161 of a substantially U-shaped roller frame 162. The roller frame 162 is pivotally mounted on a rod 163 the ends of which extend through the legs 161 of the frame 162. As shown in Fig. 8, one end of rod 163 is positioned in an opening in a boss 164 on the inner face of standard 34 while the other end of rod 163 is positioned in a socket 165 on the side wall 98 of the casing 35. Rod 163 is retained in position by means of collars 166 affixed by set screws 167 and positioned between legs 161 of the roller frame and the adjacent wall of standard 34 and side wall 98 of casing 35 respectively. Each leg 161 has a stud 168, Fig. 5a, near the pivot point of the roller frame 162 and extending laterally therefrom, to each of which studs is affixed the lower end of a coil spring 169. The upper ends of the coil springs 169 are affixed respectively to studs 171 extending laterally from the opposed inner face of standard 34 and side wall 98 of the casing 35, thereby pivoting roller frame 162 about rod 163 to urge take-up tension roller 158 against drum 146.

Journalled in a socket in the side wall 98 of the casing and in a socket in boss 164 on the inner face of the standard 34 is a rod 173 which as shown in Fig. 5a has flattened cam portions 175 along the length thereof which normally rest on the upper edges of the legs 161 of frame 162. A lever 176 is affixed to said rod 173 near one end thereof and extends downwardly between leg 161 and standard 34.

Thus when lever 176 is lifted it will rotate the flat cam portions 175 to force legs 161 downwardly, thereby moving the tension roller 158 away from drum 146, the raised lever acting as a "tell-tale" to indicate the spacing of drum 146 and roller 158.

OPERATION

To facilitate a clear understanding of the operation of the specific embodiment of loom shown in the drawings to illustrate my invention, the weaving of a strip of fabric having twenty-five warp threads, seven of which are of rubber and eighteen of which are cotton will be described in detail.

Referring now to Fig. 13, the cotton and rubber warp threads referred to by the letters *a* to *x* inclusive are wound on a warp beam (not shown) in back of the machine.

In order to produce a simple in and out weave, for example, it is necessary that the odd warp threads *a*, *c*, *e*, etc. be vertically spaced from the even warp threads *b*, *d*, *f*, etc. to permit the passage of the needle 52 therebetween. Although to achieve this end, two heddle plates would suffice, one carrying the even threads *b*, *d*, *f*, etc. and the other the odd threads *a*, *c*, *e*, etc., such arrangement would lack versatility for the larger the number of heddle plates the greater the variety of patterns that can be woven and in the high speed loom herein described twelve heddle plates have been illustratively shown.

The warp threads may be so distributed that each of the multiplicity of heddle plates controls the minimum number of threads practically feasible. Accordingly the greatest number of variations in the relative movements of the warp threads may be achieved by the arrangement of the cams on the pattern chain without the need for re-threading the heddle plates for each pattern to be woven.

Also the threads will be distributed equally among the heddle plates to minimize the tension on any one plate.

A desirable arrangement for setting up the warp threads to afford the versatility above noted and shown in Fig. 13 is as follows:

The first warp thread *a* which is of cotton is passed through the first heddle wire of heddle plate 305¹, the second warp thread *b* of cotton is passed through the first heddle wire of heddle plate 305², the third warp thread *c* of cotton is passed through the first heddle wire of heddle plate 305³ and the fourth warp thread *d* which is of rubber is passed through the first heddle wire of heddle plate 305¹². The fifth warp thread *e* of cotton is passed through the first heddle wire of heddle plate 305⁴, the sixth warp thread *f* of cotton is passed through the first heddle wire of heddle plate 305⁵, the seventh warp thread *g* of cotton is passed through the first heddle wire of heddle plate 305⁶, the eighth warp thread *h* which is of rubber is passed through the second heddle wire of heddle plate 305¹². The ninth warp thread *i* of cotton is passed through the first heddle wire of heddle plate 305⁷, the tenth warp thread *j* of cotton is passed through the first heddle wire of heddle plate 305⁸, the eleventh warp thread *k* of cotton is passed through the first heddle wire of heddle plate 305⁹, the twelfth warp thread *l* which is of rubber is passed through the third heddle wire of heddle plate 305¹². The thirteenth warp thread *m* of cotton is passed through the first heddle wire of heddle plate 305¹⁰, the fourteenth warp thread *n* of cotton is passed through the first heddle wire of heddle plate 305¹¹, the fifteenth warp thread *o* of cotton is passed through the second heddle wire of heddle plate 305¹, and the sixteenth warp thread *p* of rubber is passed through the fourth heddle wire of heddle plate 305¹².

This arrangement is repeated until all the warp threads are passed through the heddle wires of the associated heddle plates, each thread passing through the eye of but a single heddle wire. It is to be noted that in the simple illustrative arrangement above described no two adjacent warp threads pass through the eyes of the heddle wires in the same heddle plate. As the result of this arrangement the odd and even warp threads may be displaced with respect to each other as alternate heddle plates are reciprocated and each heddle plate will carry the smallest number of warp threads possible with the exception of heddle plate 305¹² which carries six rubber warp threads

in accordance with the usual procedure of having all the rubber threads change their position from over to under after each pick.

Also desirably passing through the sixth heddle wire in heddle plate 305¹² along with the rubber warp thread x is the edge wire 426 which is affixed at its rear end (not shown) to the frame and which extends parallel to warp thread x under the bridge 413 and which serves to strengthen the border of the fabric as it is woven. However, because of the larger diameter of the rubber thread, the edge wire 426 may be in a separate heddle wire.

After the 24 warp threads are positioned as above described, they are passed under bridge 413 which is pivoted to open position, and between take-up drum 146 and roller 158 which is spaced therefrom by lever 176 to permit the passage of the warp threads therebetween. The bobbin warp thread R is thereupon threaded through slit 409 in support 408, through slit 215 in the bobbin case, passed in back of tension arm 216 and through notch 213 in support horn 211 and along groove 212 therein lengthwise of said horn to the end thereof. Thread R is thereupon passed around roller 420 and along edge wire 214 beneath bridge 213 so as to extend between take-up drum 146 and roller 158.

Bridge 413 is closed and lever 176 is thereupon released so that roller 158 is resiliently urged by springs 169 against drum 146 to clamp the twenty-five warp threads therebetween.

By manually pushing on driving clutch member 149 shown in Figs. 2 and 3 it may thereupon be slid away from drum 146, this movement being possible inasmuch as ball 151 is only resiliently retained in depression 154. As teeth 148 of clutch member 149 will no longer engage teeth 147 of drum 146, the sleeve 145 is free to be rotated on shaft 138. The operator thereupon turns handwheel 155 so as to pull the warp threads between drum 146 and roller 158. When sufficient tension has been applied to the warp threads while still holding the handwheel to prevent rotation thereof, the operator slides clutch member 149 back against drum 146 so that teeth 147 and 148 are in mesh at which time ball 151 will be snapped into depression 154 on shaft 138. Thus drum 146 will be securely retained against rotation under the urging of the tensed warp threads as shaft 138 will not rotate until the main drive shaft 56 is actuated.

As the horizontal arms 313 and 314 of the heddle plates are behind the vertical leg 308, the drag of the tensed warp threads on the heddle wires carried by the horizontal legs will tend to pull the latter against vertical leg 308 between the associated pairs of bent ears 311. Thus the rivets 322 will have no horizontal strain and as the ears 311 also prevent vertical movement of horizontal arms 313 and 314 the rivets will have no vertical strain.

The next step in setting up the machine is to thread needles 52 and 52' at each end of the machine. This is done as follows:

As shown in Fig. 19 the weft thread W from spool S is passed through eye 228 rigid with the front wall of the machine and then between the discs 241 of tension device 232. The thread W is then passed in back of tension device 231 so as not to be engaged thereby and over stud 229 rigid with the front wall of the machine. The thread W is thereupon passed between take-up discs 63 and 64 around web 66 therebetween, through opening 281 in bracket 278 and opening 277 in tension compensation arm 255 and through eye 30' at the end of needle 52. The thread W extends the length of the needle and is passed through eye 30 at the nose thereof as shown in Figs. 13 and 14a. As can be clearly seen in Fig. 13, the end of the thread W is thereupon tied as at T to rubber warp thread x .

Needle 52' is threaded in a similar manner as needle 52 except that the thread W' comes off spool S' and is passed through eye 230 rigid with the frame, then be-

tween discs 241 of tension device 231, over stud 229, between take-up discs 64 and 65 and around web 67. Thread W' is thereupon passed through opening 279 in bracket 278 through support 290 shown in Figs. 2 and 3, through bracket 282 and the opening at the end of tension compensating arm 255' and through the eye at the end of needle 52'. The thread W' extends the length of needle 52' and is passed through the eye at the nose thereof. The end of thread W' is then tied to the rubber warp thread on the other end of the machine as shown in Fig. 2.

The next step in setting up the machine is to set the pattern chain. It is to be noted that to weave an "in and out" pattern such as the one to be illustratively described it is necessary that the weft thread carried by the needle be introduced between alternate warp threads. Thus heddle plates 305¹, 305³, 305⁵, etc. must be raised and lowered simultaneously to lift the odd warp threads a , c , e , etc. The length of the pattern chain is therefore arranged so that there are an even number of units of four links therein and pattern keys 114 are inserted in those grooves in pins 111 of the pattern chain aligned with the rollers 338 on the levers connected to the heddle plates 305¹, 305³, 305⁵, etc., i. e., levers 328¹, 328³, 328⁵, etc. respectively.

It is apparent that where a pattern is desired which would require an odd number of units, it is a simple matter to remove a unit of four links from the chain and where a different pattern is required using an even number of units of four links in the chain, it is a relatively simple matter to change such even pattern by merely shifting the cams, which operation will take but a few minutes and does not require disassembly of the machine.

As shaft 95 which drives the keys 114 rotates 90 degrees for each reciprocation of the needle rod 51, it is necessary in order that the needle may enter and withdraw from the warp thread before they reverse their position, that sufficient keys be used to occupy 90 degrees of the sprocket wheel 101, and as illustratively shown at the right hand end of Fig. 2, the point of the needle is withdrawn from the edge of the woven strip a distance sufficient to provide the necessary time for the reed to move forward to beat up the last woven pick after the needle point has emerged from the shed.

The positioning of the keys is clearly shown in Fig. 11. Thus, for example, when roller 338 on lever 328¹ is engaged by the sloping forward edge 117 of the first key 114, the lever will be pivoted about rod 329 to lift the associated heddle plate 305¹. With continued rotation of the pattern chain the roller 338 will ride on the top surface of the keys 114 and thereupon ride down the sloping edge 117' of the fourth key 114, at which time it has traversed 90 degrees of arc.

In order that all the odd and even heddle plates be raised at one time respectively to give an "in and out" pattern, as seen in Fig. 8, the notches designated 112^{12a}, 112², 112⁴, etc. and the notches designated 112¹, 112³, etc. respectively will have the keys therein transversely aligned across the pattern chain 101.

With the loom set up as above described, it may be manually driven for a few picks to start the weave by means of handwheel 62. As main drive shaft 56 is rotated it will also rotate gears 73 and 74 thereon; gear 74 through meshed gear 75 rotating shaft 76 and crank member 81 causing needle rod 51 to reciprocate in its bearings 49. Thus needle 52 and 52' will move in and out for each revolution of the main drive shaft. At the same time as needle 52 is moving inwardly carrying with it the weft thread W, shaft 76 is rotating worm 93 which meshes with worm gear 94 in a one to four ratio, to turn the pattern chain shaft 95 which will rotate 90 degrees with each complete reciprocation of the needle causing the alternate heddle plates to be raised to form a shed in the warp threads between the fell and the heddle plate 305¹² prior to the introduction of the needle therebetween.

Inasmuch as the weft thread W is held at one end in the woven strip, as the take-up discs rotate, web 66 will move in a clockwise direction as shown in Fig. 19 from the position occupied by web 67 and pull the thread required for the double weft pick from the spool S. In order that the thread W be able to move freely, the discs 241 of tension device 232 are separated by pin 251 under the urging of ball 239 actuated by cam 183 (Fig. 4a).

The needle will enter the shed and pass between alternate wrap threads as shown in Fig. 13, and preferably over the hook 195 as shown in Fig. 17, driven by drive shaft 56 through gears 73, 184 and 185, 186 so that hook 195 will be rotated twice for each in and out movement of the needle. The notch 406 (Fig. 24) of the leading edge 402 of the hook 195 will catch the weft thread W carried by needle 52 at the lower limb 285 thereof (Fig. 17) across the notch 28 in the underface of the needle. As the needle moves further and hook 195 continues its rotation, the thread W which is relatively slack having been pulled off spool S by web 66 will be freely pulled through the eyes 30 and 30' of the needle and as shown in Fig. 19, through opening 277 in arm 274, and through opening 281 in bracket 278.

During this time the hook 195 will have rotated sufficiently to form a loop in the thread W and a leg 286 thereof (Fig. 13) will hit the upstanding guide member 421 and be guided in slot 407 in the rear wall of the hook 195. Continued rotation of the hook 195 will cause the loop to start to encircle the bobbin case 199 and with the needle at the furthest point of its movement through the shed, the other leg 287 of the loop will start to ride up the inclined edge 408' of the bobbin case.

At this point the take-up discs will have rotated sufficiently so that web 66 will have moved approximately 100 degrees from the position occupied by hub 67 as shown Fig. 19 and the cam 183 will have rotated so that tension device 232 is now closed tightly, clamping the thread W. As hub 66 continues to rotate, it will quickly pull on the thread W, disengaging it from the hook and causing it to ride further up the inclined surface 408'.

By reason of the tension compensation member 255, as the web 66 pulls on the thread, in the event that not enough slack was pulled off spool S by the web 66, arm 274 of member 255 will pivot to provide additional slack and prevent snapping of the thread. In addition, by adjusting the knob 262 shown in Fig. 19 the tension of spring 272 on arm 274 may be regulated thereby enabling arm 274 to pivot more or less freely to determine the tension on the weft thread which must not be too great or it would cause distortion of the weave.

When leg 287 of the loop contacts tooth 202', as the latter only rests lightly on support arm 204 in the opening 200, the thread will be pulled between tooth 202' and arm 204. Leg 287 of the thread will thereupon ride over the top of the support horn 408 passing over slot 409 by reason of the inclination thereof, and as the thread is pulled further by rotation of hub 66, leg 286 will also be pulled from slot 407. Thus the loop will be carried around the support horn and consequently around the bobbin thread R. As the thread W is pulled further, from the position shown in Fig. 13, it will ride down the support horn and encircle the bobbin warp thread R and edge wire 214, and when the needle is withdrawn from the shed the loop will be pulled closed to form a filler thread across the warp.

As the bight of the loop reaches the end of the support horn it will slide between such end and roller 420 which latter will rotate to prevent undue friction on the thread with possible breaking thereof.

At this time the needle will have completely withdrawn from the shed and sprocket wheel 101 will have rotated so that rollers 113 will engage rollers 387 at the end of reed 361 thereby oscillating the latter. This will cause

5

the reed to move forward as shown in dot and dash lines in Fig. 10 so that the fingers 381 thereof interposed between the warp threads will beat the newly woven filler thread W to form a tight weave. Continued rotation of the pattern chain will cause roller 113 thereon to move away from the rollers 387 on the reed so that coil springs 373 thereof will move the latter back to its rest position against stop 389.

As the take-up drum rotates one revolution for each 10 240 reciprocations of the needle rod, it is apparent that if the drum has a diameter of one and one half inches, approximately .8 inch of strip will be moved for every 40 reciprocations of the needle and hence such weave will have approximately 50 double threaded picks per inch.

15

It is to be noted that the speed at which the woven material is pulled forward between drum 146 and roller 158 depends upon the diameter of drum 146 and the speed at which it rotates. By increasing or decreasing 20 the speed of the take up drum the number of picks per inch can be decreased or increased respectively as desired, for the slower the speed the greater the number of picks per inch. This change of speed may be readily accomplished by replacing gear 132 (Fig. 7) with another gear of different size. This is conveniently done by removing nut 131 and loosening nut 137 so that idler gear 133 can be disengaged from gear 132 which is then replaced. Adjustment plate 134 is thereupon pivoted about shaft 138 until the teeth of idler gear 133 mesh with the teeth on the substituted gear 132, whereupon nut 137 is retightened. As the teeth on idler gear 132 are always in mesh with the take-up shaft spur gear 141, the latter will be driven by replacement gear 132.

25

As the drum slowly pulls on the woven strip, the borders thereof will be withdrawn from the edge wires which prevent transverse distortion of the strip during weaving.

30

If during the operation of the loom any of the warp threads should break, it is a relatively simple matter to tie the broken ends of the warp thread. Thus, the bridge 413 may be lifted as heretofore described. One of the broken ends of the warp thread is passed through the eye of a conventional needle which is thereupon passed through the eye 322 of the appropriate heddle wire. As the distance between the first and last heddle plates is small, this is a relatively simple procedure.

35

Thus by the construction herein described, a high speed loom has been provided in which the weight and strokes of the reciprocating parts have been brought to a minimum and uniform rotary motions have been used in substantially all cases. The loom parts may be small in size and light in weight and will function with a minimum of shock. By reason of the simple means of changing the order of reciprocation of the heddle plates, the pattern of the weave may quickly be changed without any undue interruption in operation.

40

Although the operation of but one of the operating stations of the loom has been described, it is of course to be understood that as both of the operating stations 60 are substantially symmetrical, they will both function in a similar manner with a phase separation of 180 degrees.

45

As substantially all moving parts are enclosed in oil there is little danger of rapid deterioration of the machine 65 due to the collection of dirt and dust or of jamming thereof and also any danger or injury to the operator is averted.

50

As many changes could be made in the above construction, and many apparently widely different embodiments of this invention could be made without departing from the scope of the claims, it is intended that all matter contained in the above description or shown in the accompanying drawings shall be interpreted as illustrative 70 and not in a limiting sense.

Having thus described my invention, what I claim as new and desire to secure by Letters Patent of the United States is:

1. In a loom of the type for weaving narrow fabric comprising heddle plates, means to reciprocate the same to form a shed having a fell, a reed, a weft needle associated with said heddle plates, and means to reciprocate said needle into and out of said shed; wherein the heddle plates are of thin sheet stock and in close proximity to each other and in which the needle passes through such shed in a path contiguous to said fell and near the first heddle plate, the reed and the needle being of dimensions conjointly substantially to fill the shed.

2. The combination set forth in claim 1 in which said reed member comprises a light weight plate having a yoke at the lower end thereof whereby said plate may be pivoted, and a comb at the upper end thereof comprising a plurality of narrow parallel upstanding fingers.

3. In a loom of the type for weaving narrow fabric, comprising heddle plates, means to reciprocate the same to form a shed having a fell, a weft needle associated with said heddle plates, and means to reciprocate said needle into and out of said shed; wherein the heddle plates are of thin sheet stock and in close proximity to each other and in which the needle passes through such shed in a path contiguous to said fell and near the first heddle plate, said needle having an elongated body portion with an elongated notch on its underside at the nose thereof across which the weft thread extends when the needle has passed into the shed, a hook, a bobbin associated with said hook and carrying a warp thread, means to actuate said hook to pass the latter through the notch in said needle when the latter has been advanced into the shed, thereby engaging the portion of such weft thread extending over said notch, and means to pass such weft thread around such bobbin warp thread.

4. In a high speed loom for weaving narrow fabric, small, light weight, closely spaced, thin sheet metal heddle plates, small light weight levers to reciprocate the heddle plates for forming a shed having a fell, a light weight thin narrow needle which passes through the shed adjacent the fell, a small light weight reed having narrow beating up elements positioned adjacent the needle and the first heddle plate, whereby the small size, light weight and compact arrangement of said heddle plates, levers, reed, needle and fell provide for short strokes and low inertia forces of said reciprocating elements and for high speed operation of the loom, said loom including rotary weft locking means and rotary weft controlling means.

5. In a loom of the type for weaving narrow fabric comprising heddle plates, means to reciprocate the same to form a shed having a fell, a horizontally reciprocable weft needle associated with said heddle plates, and means to reciprocate said needle into and out of said shed; wherein the heddle plates are of thin sheet stock and in close proximity to each other, in which the needle passes through said shed in a path contiguous to said fell and near the first heddle plate and in which the means to reciprocate the heddle plates comprises a downwardly extending finger on each of the heddle plates, a plurality of pivoted levers, a rocker connection between each of said levers and each of said fingers, rotary drive mechanism and a transmission from said rotary drive mechanism to each of said levers to actuate the same, said rocker connection comprising a tip at the end of each finger, each lever having a corresponding transverse arcuate depression at its end in which said tip may be seated, and a cap member at the end of the lever.

6. A loom comprising a casing, rotary drive mechanism in said casing, a pair of guide plates, each having a plurality of closely spaced vertical grooves therein respectively transversely aligned with each other, warp carrying heddle plates slidably mounted in said grooves, lever means operatively connected to each of said heddle plates, a transmission from said rotary drive mechanism to actu-

ate said levers whereby said heddle plates may be reciprocated to form a shed having a fell in such warp threads, a needle for carrying a weft thread and means to pass the latter through said shed in a path contiguous to said fell and near the first heddle plate.

7. A loom comprising a casing, rotary drive mechanism in said casing, a plurality of vertical closely spaced heddle plates associated with said casing, each of said heddle plates having a downwardly extending finger, a plurality of pivoted levers, a rocker connection between each of said levers and one of said fingers, a rotatable wheel in juxtaposition to said levers, a transmission from said rotary drive mechanism to rotate said wheel, means carried by said wheel and operatively connected to each of said levers to actuate the same whereby said heddle plates may be reciprocated to form a shed having a fell, a needle for carrying a weft thread, means to reciprocate said needle and pass the latter into and out of said shed, in a path contiguous to such fell, a pivoted reed, and means to oscillate said reed toward and away from such fell to beat said weft thread to form the woven strip.

8. A loom comprising a plurality of reciprocable heddle plates, lever means operatively connected to each of said heddle plates, a pivoted reed associated with said heddle plates, a rotatable sprocket wheel, a transmission to rotate said sprocket wheel, an idler sprocket wheel rotatably mounted beneath said rotatable sprocket wheel, a pattern chain carried around said sprocket wheels, cam means detachably connected to said pattern chain and respectively moved against said levers to pivot the latter whereby said heddle plates may be lifted to form a shed, and means on said chain coacting with said reed member to pivot the latter.

9. The combination set forth in claim 8 in which the reed member has a comb extending parallel to said heddle plates, a stop is provided for said reed and resilient means normally retain said reed against said stop.

10. The combination set forth in claim 8 in which said chain has a plurality of rollers thereon which are operatively connected to said reed to pivot the latter.

11. The combination set forth in claim 8 in which the lower portion of said pattern chain and said idler sprocket wheel are enclosed in an oil-tight casing.

12. The combination set forth in claim 8 in which each of said levers has a roller rotatably mounted on the side thereof and against which said cams move.

13. The combination set forth in claim 8 in which said pattern chain has a plurality of spaced parallel elongated pins connecting the sides thereof, said pins each having a plurality of spaced circumferential grooves therein aligned with one of said levers and with corresponding grooves in adjacent pins.

14. The combination set forth in claim 13 in which said sprocket wheel has a plurality of spaced circumferential grooves therein aligned respectively with the grooves in said pins, and each of said cams has legs which straddle two adjacent pins and extend therebelow, said legs riding through and extending in the grooves in said sprocket wheel as the latter is rotated, whereby when said cams move against said levers said cams will be retained in upright position without tilting.

15. The combination set forth in claim 13 in which each of said cams comprises a substantially U-shaped member of resilient material, the legs of which have an arcuate notch in opposed faces thereof, whereby when said cam is inserted into the aligned groove of two adjacent pins with the legs straddling said pins the latter will be seated in said notches and said cam will be retained in place by reason of the resiliency thereof, said cam having a curved upper edge against which a lever moves.

16. As an article of manufacture, a cam key for pattern control on textile machines, comprising a substantially U-shaped member having notches in the opposed edges of the legs thereof, the cross piece of said cam key hav-

ing a sloping portion and a curved portion on the upper edge thereof.

17. A loom for weaving narrow fabric, said loom comprising a plurality of closely spaced heddle plates, means to reciprocate said heddle plates to form a shed, a needle for carrying a weft thread, means to reciprocate said needle into and out of such shed, a table plate associated with said heddle plates, and lying in a plane at right angles thereto and in front thereof, a substantially cup-shaped bobbin case, means to support said bobbin case, a substantially cup-shaped hook encompassing said bobbin case, a bobbin rotatably mounted in said bobbin case and carrying a warp thread thereon, a support horn rigid with said bobbin case and extending inwardly therefrom over said table plate, and along which such bobbin warp thread is positioned, and means to rotate said hook to form a loop in such weft thread and pass such loop around said bobbin case and said support horn to encircle such bobbin warp thread.

18. The combination set forth in claim 17 in which the means to support said bobbin case comprises an upstanding support plate on the upper edge thereof, a support tooth on said support plate extending laterally outward therefrom, and a support arm having an opening therein in which said tooth is inserted.

19. The combination set forth in claim 18 in which said support plate has a resilient arm affixed to the rear face thereof to tension the bobbin warp thread positioned along said support horn.

20. The combination set forth in claim 17 in which the mouth of said bobbin case flares outwardly whereby when said weft thread is engaged by said hook and passed around said bobbin case said flared portion will disengage said thread from said hook.

21. The combination set forth in claim 17 in which said cup-shaped hook member has a notch in the side wall thereof forming oblique angles with the rear wall thereof, one of the edges of the notch being beveled and having a metal strip affixed thereto to form a groove, said hook member adjacent the rear wall thereof having a peripheral slot therein extending from the edge of said groove adjacent said rear wall to nearly the other edge of said notch.

22. The combination set forth in claim 17 in which said support horn has an edge wire affixed at the end thereof and extending at right angles thereto toward the front of said loom and along which the bobbin thread extends.

23. The combination set forth in claim 17 in which a displaceable bridge is positioned on said table plate parallel to said heddle plates and in front thereof, and beneath which such woven strip extends.

24. The combination set forth in claim 23 in which an upstanding roller is mounted on said table plate between the end of said support horn and the displaceable bridge whereby said support horn will be restrained from lateral displacement yet such weft thread may readily slide between said roller and the end of said support horn.

25. The combination set forth in claim 23 in which a substantially U-shaped hinge member is affixed to said table plate adjacent the end of said support horn with the legs of said hinge member extending longitudinally of said plate and pivotally mounting one end of said bridge, and a laterally extending lip at the free end of said bridge coacting with a notch in said table plate releasably to retain said bridge against said table plate.

26. A loom comprising a plurality of warp carrying heddle plates, a transmission to reciprocate said heddle plates to form a shed in such warp threads, a needle for carrying a weft thread, a transmission for reciprocating said needle into and out of said shed, a hook, a bobbin associated with said hook for carrying a warp thread thereon, a transmission to rotate said hook and pass such weft thread around said bobbin, and a rotary slack take-

up mechanism to draw the weft thread about said bobbin warp thread.

27. The combination set forth in claim 26 in which the rotary slack take-up mechanism comprises a pair of rotating elements, and a connecting member which draws the weft thread around said bobbin warp thread.

28. The combination set forth in claim 26 in which means are provided to clamp such weft thread when said slack take-up is operating.

29. The combination set forth in claim 28 in which the means to clamp such weft thread comprises a pair of tension discs between which such weft thread passes, resilient means maintaining said discs in juxtaposition and clamping such weft thread therebetween, means to separate said discs to release the grip on such weft thread, and a transmission to actuate said last named means in timed relation with the rotation of said slack take up.

30. The combination set forth in claim 28 in which the means to clamp on such weft thread comprises a pair of discs between which such weft thread passes, resilient means maintaining said discs in juxtaposition and clamping said weft thread therebetween, a releasing rod adapted to move against the outermost one of said discs, a rotatably mounted cam against which the free end of said releasing rod moves, and a transmission to rotate said cam and reciprocate said releasing rod to separate said discs in timed relation with the rotation of said slack take up.

31. A loom comprising a casing, a transverse drive shaft in said casing, a plurality of warp carrying heddle plates, a transmission from said drive shaft to reciprocate said heddle plates to form a shed in such warp threads, a needle rod mounted on said casing, a needle for carrying a weft thread, a transmission from said drive shaft for passing said needle into and out of said shed, a hook, a bobbin associated with said hook for carrying a warp thread thereon, a transmission from said drive shaft to rotate said hook and pass such weft thread around said bobbin, slack take up mechanism for such weft thread comprising a disc affixed to the end of said transverse shaft, a second disc coaxial with said first disc, a web connecting said discs near the periphery thereof and spacing the two, whereby when such weft thread passes between said discs, said web will move against such weft thread to draw the latter around said bobbin warp thread, and means to clamp and to release such weft thread in timed relation with the rotation of the slack take-up mechanism.

32. A loom comprising a casing, rotary drive mechanism in said casing, a standard on said casing, a pair of guide plates fixed respectively on the opposed faces of said standard and said casing, said plates each having a plurality of closely spaced vertical grooves respectively aligned with each other, a warp carrying heddle plate slidably mounted in each pair of aligned grooves, lever means operatively connected to each of said heddle plates, resilient means connected to each of said levers to retain said heddle plates in their lowermost position, a sprocket wheel positioned between said standard and said casing, a transmission from said rotary drive mechanism to rotate said wheel, a wide idler sprocket wheel mounted beneath the bed of said loom, a pattern chain carried by said sprocket wheels and having a plurality of parallel elongated pins each having a plurality of spaced circumferential grooves therein aligned with one of said levers and with corresponding grooves in adjacent pins, detachable cams adapted to be inserted into the aligned grooves of two adjacent pins, said cams moving against associated levers as said sprocket wheel is rotated to pivot said levers whereby some of said heddle plates may be raised to form a shed having a fell, a horizontal needle carrying a weft thread, means to reciprocate said needle and pass the latter into and out of such shed in a path contiguous to said fell and near the first heddle plate, a bobbin case, a substantially cup-shaped hook encompassing said bobbin case, a bobbin mounted in said bobbin case and carrying a warp thread, a transmission from said rotary drive mechanism to rotate said hook and pass such weft thread around said

bobbin warp thread to form the woven strip, a reed member pivoted between said standard, a stop for said reed, resilient means normally retaining said reed against said stop, means carried by said pattern chain to pivot said reed toward said feel, said reed having a plurality of upstanding fingers at the upper end to pack said weft thread as said strip is woven.

33. As an article of manufacture, a sheet metal heddle plate comprising a base, an upstanding leg on one end of said base having laterally projecting tongues near said base and the top of said leg respectively, an upstanding leg on the other end of said base having a pair of laterally extending heddle carrying rails near the base and at the top of said leg respectively and affixed at their respective ends to an associated tongue, and a finger on said base and extending downwardly therefrom.

34. The article of manufacture as set forth in claim 33 in which the heddle plate is made from a single piece of sheet metal.

35. As an article of manufacture, a sheet metal heddle plate comprising a base piece, an upright leg at each end of said base piece, two heddle carrying rails extending from one of said legs and positioned behind the other leg, releasable connection elements on the rails and the legs and thrust receiving elements straddling the rails.

36. The article of manufacture as set forth in claim 35 in which an operating element extends downward from the base piece.

37. The article of manufacture as set forth in claim 35 in which the tip of the operating element has a cylindrical rocker joint conformation.

38. In a loom of the type for weaving narrow fabric which includes a casing, a weaving head at each end of said casing, each of said weaving heads including a set of warp carrying heddle plates of thin sheet stock and in close proximity to each other, means to reciprocate the same to form a shed having a fell, a weft inserting needle which passes through such shed in a path contiguous to said fell and near the first heddle plate, a weft locking means and a woven fabric take-up means, said casing containing a common operating mechanism for both said weaving heads.

39. A loom for weaving narrow fabrics, comprising a casing, a transverse drive shaft in said casing, a weaving head at each end of said casing, each of said heads having a plurality of warp carrying heddle plates, a transmission from said drive shaft to reciprocate said

heddle plates alternatively at each of said heads to form sheds each having a fell, a horizontal needle rod mounted on said casing, a needle at each end of said needle rod each carrying a weft thread, a transmission from said drive shaft for reciprocating said needle rod to pass said needles into and out of the associated shed in a path contiguous to said fell and near the first heddle plate, a hook at each of said heads, a bobbin associated with each of said hooks for carrying a warp thread thereon, a transmission from said drive shaft to rotate said hooks and pass such weft thread around the associated bobbin, slack take-up mechanism for such weft threads comprising a disc affixed to the end of said transverse shaft, a second disc coaxial with said first disc, a web connecting said discs near the periphery thereof and spacing the two, a third disc coaxial with said first and second discs, a web connecting said third disc and said second disc near the periphery thereof, spacing said discs and displaced 180 degrees from said first mentioned web, whereby when one of such weft threads is passed between the first and second discs and the other of such weft threads is passed between said second and third discs and the latter are rotated, said webs will alternately draw the latter around the associated bobbin warp thread to form the woven strip at each head.
